(57) **CLAIM**The ornamental design for footwear upper, as shown and
 described.

DESCRIPTION

FIG. 1 is a perspective view of the footwear upper embodying
 the new design;

FIG. 2 is a front elevational view thereof;

FIG. 3 is a rear elevational view thereof;

FIG. 4 is a top plan view thereof;

FIG. 5 is a right side elevational view thereof; and,

FIG. 6 is a left side elevational view thereof.

FIGS. 1-6 show an outsole in broken lines. The outsole is
 shown for environmental purposes and does not form any
 part of the claimed design.The broken lines which form the bounds of the claimed
 design form no part thereof.**1 Claim, 6 Drawing Sheets****Fig. 1**
